UNITED STATES PATENT OFFICE.

CLARENCE GRANGER WHITE, OF SPOKANE, WASHINGTON.

OIL-BURNING APPARATUS.

1,088,758.

Specification of Letters Patent.

Patented Mar. 3, 1914.

Application filed December 23, 1912. Serial No. 738,226.

To all whom it may concern:

Be it known that I, CLARENCE GRANGER WHITE, a citizen of the United States, residing at Spokane, in the county of Spokane and State of Washington, have invented new and useful Improvements in Oil-Burning Apparatus, of which the following is a specification.

This invention relates to improvements in oil burning apparatus of the general type disclosed in U. S. Patent 791,813, issued June 6, 1905, to Jake Palmatary.

It is one of the objects of this invention to provide certain improvements whereby very cheap and inexpensive fuel oil may be used with a high degree of thermal efficiency, it being possible with the device of my invention to use what is termed "topped oil".

20 A further feature of this invention consists in improved means for generating initial heat, when starting the burner, to operate a steam generator and thin the oil in a very quick and efficient manner.

25 Other features and novel parts of the invention will be more fully described in connection with the accompanying drawing and will be more particularly set forth in and by the appended claims.

30 In the drawing: Figure 1 is a perspective view of a form of apparatus embodying one construction of my invention. Fig. 2 is a plan view thereof with parts in section. Fig. 3 is a sectional view of an oil feeding pipe. Fig. 4 is a sectional view of an atomizing burner head.

Like characters of reference designate similar parts throughout the different figures of the drawing.

40 As illustrated, a support preferably in the form of a firing pan 1 is provided with standards 2 and 3 in which a steam generator 4 is mounted. The steam generator 4 is in the form of a pipe which is closed at the right hand end thereof and which is mounted in standards 2 and 3. The left hand end of the pipe 4 is provided with any suitable form of stuffing box 5 through which an extension 6 of a water pipe 7 projects. The

50 water pipe 7 is provided with a valve 8 for controlling flow therethrough. The water pipe extension 6 is reduced in diameter with respect to the internal diameter of pipe 4 so as to provide an intermediate space for the generation of steam. The right

hand end of the water pipe extension 6 is open so as to discharge into pipe 4 near the closed end 10 thereof.

A heating element of high heat conductivity, such for instance as a copper wire indicated at 11, may be bent U-shaped or formed with one leg 12 extending through a suitable fitting 13 in the wall 10, the leg 12 extending practically the entire length of the steam generator 4. That portion of the leg 12 adjacent the discharge end 9 of pipe extension 6 may be coiled or spiraled, as indicated at 14, to increase its heat radiating surface. The remaining leg 15 extends over the pan 1 and may be coiled or spiraled as at 16 to increase its heat inductive capacity or surface adjacent to the point where the heating element is subjected to the initial or starting flame.

It will be clear from the foregoing that when the element 11 is heated by the initial or starting flame it will cause generation of steam in the pipe 4 when water is discharged therein through extension 6. Steam is drawn off from the generator 4 through a pipe 17 which connects with a T-fitting 18 and pipe 19 which latter delivers to a burner head 20. A plunger valve 21 provided with a stem 22 projecting through said T-fitting 18, and having a handle 23, serves to regulate the passage of the steam to the burner 20. The burner 20 is provided with an atomizing duct 24 having a flared terminal 25 from which the steam is discharged to atomize the oil. A main fuel oil duct 26 delivers to the flared terminal 25 so that the rapidly passing or discharging steam will atomize the fuel in accordance with the well-known action of such device.

A starting oil duct 27 delivers abreast of the flared terminal 25 so that its discharging contents may be subjected to the action of the steam. A pipe 28 leading to the duct 27 may be connected with any suitable source of supply of oil, of the lighter type, as for instance a tank 29. An oil heating pipe 30 is connected at one end with a valved supply pipe 31 and is provided with a suitable stuffing or packing box 32, at its other end. A heating element, preferably in the form of a copper wire 33 is coiled at 34 to present increased heat inductive surface to the initial flame and the wire 33 extends through the stuffing box 32 into the pipe 30 and substantially throughout the length thereof. The

wire 33 is coiled at 35 and 36 to present an increased heat radiating surface to send the oil flowing through the pipe 30. The pipe 30 is connected by a pipe 37 to a valve 38 and the latter is connected by a pipe 39 with the burner head 20 so as to deliver to the duct 26.

By reason of the fact that the oil is heated by wire 33, before it reaches the burner head 20, and by reason of the fact that the oil is thinned by the application of such heat I am enabled to use any kind of oil such as the heaviest weight oils, as for instance topped oil, which latter gives a very hot flame and which is practically 50% cheaper than any other known fuel oil. By heating the oil it not only flows freely to the burner head 20 but I am also enabled to absolutely prevent carbonization. The steam used for atomizing the oil effectively prevents soot and smoke, which is a waste of fuel, and which provides for an absolutely clean flame.

In the use of my invention the water pipe 25 may be connected with a city main or any suitable source of supply of water under pressure, say approximately 30 pounds. The wires 11 and 33 are presented to the initial flame issuing from the discharge of 30 lighter oil from duct 27 into the pan to initially heat the parts. Immediately upon heating the wire 15 steam is generated without the usual delay so inconvenient in devices at present in use. By initially heating 35 the oil, at the time that the steam is generated and by the initial flame, I also gain appreciably, in the question of time, in starting the burner.

It will be understood that the burner may 40 be operated by the lighter oil flowing through duct 27, alone, or the heavier oil flowing through duct 26, alone, or the two may be jointly used where an extremely low grade of oil is supplied to duct 26.

45 While I have herein shown and described one specific form of my invention I do not

wish to be limited thereto except for such limitations as the claims may import.

I claim:

1. An oil burner comprising in combination, a burner head, an oil container delivering to said burner, means for delivering a fluid under pressure to said burner to discharge oil therefrom, and a metallic element having a portion thereof disposed in said container and a portion thereof lying exterior to said container and adapted to be heated to transmit heat to the oil in said container prior to its delivery to said burner, substantially as described. 50

2. An oil burner comprising in combination, a burner head, an oil container delivering to said burner head, means for delivering fluid under pressure to said burner to cause discharge of oil therefrom, and means disposed partly inside and partly outside 60 of said container and adapted to have its outer portion heated to transmit heat to the oil in said container prior to the delivery of such oil to said burner, substantially as described. 65

3. An oil burner comprising in combination, a firing pan, a burner head adapted to deliver a flame over said pan, an oil chamber delivering to said burner, a steam generator delivering to said burner to cause a discharge of the oil therefrom, a wire in and projecting from said oil chamber and having its projecting portion extended over said pan, and a wire in and projecting from said generator and having its projecting portion 75 extending over said pan, projecting portions of said wires being adapted to be heated by the starting flame from said pan, substantially as described. 80

70
In testimony whereof I affix my signature 85 in the presence of two witnesses.

CLARENCE GRANGER WHITE.
